UNITED STATES PATENT OFFICE.

ARTHUR J. BAZELEY, OF CLEVELAND, OHIO, ASSIGNOR TO THE NATIONAL MALLEABLE CASTINGS COMPANY, OF CLEVELAND, OHIO, A CORPORATION OF OHIO.

CAR-COUPING.

1,128,652.

Specification of Letters Patent. Patented Feb. 16, 1915.

Application filed August 10, 1910. Serial No. 576,549.

To all whom it may concern:

Be it known that I, ARTHUR J. BAZELEY, a citizen of the United States, and a resident of Cleveland, county of Cuyahoga, State of Ohio, have invented a new and useful Improvement in Car-Couplers, of which the following is a full, clear, and exact description, reference being had to the accompanying drawings, forming part of this specification, in which—

Figure 1 is a sectional plan view of a coupler constructed in accordance with my invention showing the parts in locked position; Fig. 2 is a sectional side elevation of the same; Figs. 3 and 4 are detail views of the knuckle-throwing lever; Fig. 5 is a detail view of the bottom-operating lever; Figs. 6 and 7 are enlarged side elevations of the locking block; Figs. 8, 9 and 10 are longitudinal vertical sections showing the parts in locked, in lockset and in knuckle-thrown position, respectively, and Figs. 11, 12 and 13 are cross sectional views corresponding, respectively, to Figs. 8, 9 and 10, Fig. 11 showing the locked position, Fig. 12 the lockset position, and Fig. 13 the knuckle-thrown position. Fig. 14 shows a detail section on line X—X of Fig. 2.

My invention relates to car couplers of the type set forth in my copending application No. 539,258, filed January 21st, 1910.

The object of the present invention is to improve the action of my coupler described in said application, the main feature being the lifting of the lock through a part of its movement by the operating lever itself, so that the lock need not be lifted by the knuckle tail when the tail is thrown open. The tail is provided with a raised surface, which holds the lock in proper position to drop to its seat when the knuckle is closed, and this raised portion also releases the lockset when the lock is raised to lockset position and the knuckle is pulled open. As in my previous case, the knuckle-throwing lever acts as a lockset, and also a lock to the lock, but in the present form is at least partially released from its lifting of the lock, its function being partially transferred to the operating lever.

A further feature lies in shaping the knuckle-throwing lever with an abruptly rounding cam surface, on which the operating lever will roll with less friction and without the rapid change of leverage pres-

ent in the former device. This renders the knuckle-throwing movement easier and more positive.

In the drawings 2 represents the head of the coupler, and 3 the knuckle. The knuckle tail 4 is provided with an angular bearing surface 5 for the locking block 6. This bearing surface extends at an angle to the line of draft and fits the correspondingly inclined face of the locking block. The tail 60 is also provided upon its opposite side with an angular projection 7, which enters a correspondingly shaped recess 8, in the wall of the coupler head, and has a forwardly inclined face 9, fitting the correspondingly inclined face of the coupler head recess, so as to draw against it, when in closed position. These engaging parts are preferably inclined at an angle of 45° to the line of draft. The faces 9 and 5 diverge rearwardly. The tail 70 is also preferably provided with a horn 10, which projects through a side hole in the coupler head. The faces 5 and 9 preferably extend vertically. The pivot pin hole in the hub of the knuckle is preferably 75 provided with sufficient clearance to give freedom for the knuckle in its opening and closing movements, and to allow the strain of draft to come primarily on the tail faces 5 and 9, and relieve the strain on the pin. 80 The widening of the bearing faces of the tail toward the rear end adds strength thereto, increasing the bearing surface.

The locking block 6 is shown in Figs. 6 and 7. It is of the single, vertical pin type, 90 with its front portion cut away as shown at 11 to allow passage of the knuckle tail when lifted. This cutting away leaves a shoulder 12 which rests upon the elevated top face of the horn portion 10 when the 95 knuckle is open. The upper portion of the locking block is also provided with the recess 13 preferably having a vertically inclined face 13' which bears on a vertically inclined face on the knuckle tail. This 100 gives a rearward wedging action on the tail to cause the face 9 to engage the recess in the head and provides an initial tight fit for these parts. The lower portion of the locking block is provided with a cam recess 15 105 within which the lug 16 of the knuckle-throwing lever 17 operates. This knuckle-throwing lever 17 is shown in Figs. 3 and 4, and is loosely mounted on an axle 18, which is driven horizontally inward through a 110

hole in the lower side portion of the coupler in the position shown in Figs. 1 and 2. It is held in this position by any suitable means such as a cotter pin, which may be 5 driven down through a vertical hole in the floor of the coupler cavity beyond the outer end of the pin when driven home. This knuckle-throwing lever 17 is provided with an upwardly extending push portion 20, 10 which engages the rear curved face 21 of the knuckle tail 4, to push the knuckle open after unlocking. The knuckle-throwing lever, in addition to throwing the knuckle, performs the functions of lifting the lock 15 through a portion of its movement and also co-operates with the lock to act as a lock-to-the-lock or anti-creeping device, and also as a lockset. The lock-to-the-lock function results from the coaction of an angular 20 shoulder 31 of the lug 16 with the lower shoulder 23 below the recess 15 of the locking block. When the parts are in normal locked position, any accidental upward movement of the locking block will cause a 25 toggle-like action between the lower shoulder 23 of the lock and the angular shoulder 31 of the lug, and thus tend to jam the vertical face of the locking block against the wall of the coupler. In the locksetting 30 function, as the lever 17 is pushed upwardly, this rotation brings the angular corner portion 32 of the lug 16 into engagement with the shoulder 22, forming part of the upper wall of the recess 15, of the locking block, 35 which recess is enlarged forwardly, as shown in Figs. 6 and 7. This brings the parts into lockset position, the knuckle-throwing lever then propping up the lock in a position where the knuckle can be pulled 40 open.

In my present form I provide a bottom-operating lever 25, which is pivoted between lugs 26 depending below the pivot pin hole, the hub of the lever thus also acting as a 45 pivot pin support in case of breakage. At its bend the lever is provided with a hole or eye 27 to receive the uncoupling lever of any desirable form. The upwardly curved inner portion 25a of the uncoupling lever 50 abuts against the lower outer portion of the knuckle-throwing lever 17 to lift it; and below this upper end this curved arm of the lever is provided with a side extension or lug 28, which is arranged to act directly 55 upon the lower end of the locking block 6. In the first upward movement of the lever 25, it lifts the lever 17 off its lock to the lock engagement. Immediately after this the side projecting lug 28 on the lever 25 comes 60 in contact with the bottom of the lock and lifts the lock directly. As the contact point between the lever 25 and the lever 17, however, slides inwardly closer to the pivot pin of the lever 17 in the continued movement, 65 the rotation of the lever 17 is accelerated

so that the lug 16 overtakes the upward movement of the lock, and for a short distance itself serves to lift the lock, while it in turn, is lifted by the bottom-actuating lever 25. When the lock, however, has risen 70 so that its shoulder 12 clears the tail of the knuckle and allows the latter to open, in the further actuation of the lock, the lug 28 of the lifting lever will again assume its lifting function and raise the lock entirely 75 clear of the knuckle-tail. As soon as the opening movement is complete, the lever 25 is dropped back to its normal position. At the same time, the knuckle-throwing member 17 will drop back to the new position 80 shown in dotted lines in Fig. 10, resting on the bottom of the recess in the depending leg of the lock. This is an important feature, since after the completion of the knuckle-throwing, the member 17 swings 85 back to such a position that its lug 16 will not engage the ledge 22. If this engagement between the lug 16 and ledge 22 should take place at this time, the lockset 90 position might occur and act to hold the lock in elevated position, and to retain it there even after it was no longer supported by the knuckle-tail when the knuckle was again closed. It will be understood that during the normal operation of the parts 95 wherein the lock is lifted and the knuckle thrown by the external actuation of the lever 25, the knuckle does not at any time assist in lifting the lock. Even at the completion of the knuckle-throwing movement, 100 as shown in solid lines in Fig. 10, the lock is lifted clear of the knuckle tail and is wholly supported on the lug 28. However, as soon as the lifting force is removed from the lever 25, it will drop back and allow the lock 105 to settle by a slight amount until it rests upon the raised portion of the knuckle tail and remains there until the latter is closed. It will be obvious, therefore, that the lock 110 is allowed to offer no obstruction to the pivotal throw of the knuckle during the normal knuckle-throwing movement, since it is lifted entirely clear of and is supported independently of said tail until the throwing of the knuckle is completed. When the lock is lockset and the knuckle is pulled 115 upon by hand or by the knuckle of an opposing car, however, then the lock is lifted and released from lockset position by the raised portion of the knuckle tail and remains supported thereon until the knuckle is again closed. The raised portion of the tail also acts to release the lockset when the knuckle 120 is pulled open after locksetting. In this pulling open of the knuckle, its tail lifts 125 the lock 6 slightly and allows the knuckle-throwing lever 17 to free itself from the lockset shelf and drop downwardly into the position shown in dotted lines in Fig. 10 so that when the knuckle is again closed, it 130

will not remain supported on the lockset, but will drop back to locking position. In order to make the knuckle-throwing movement easier, I provide the under-surface of the lever 17 with an abruptly rounding cam surface 17^a. This will cause the upper end of the lever 25 to roll upon its surface with less friction than in the former case, and without the rapid change of leverage, thus assisting in the knuckle-throwing action. In order to limit the downward movement of the operating lever 25 I preferably provide it with a side projection or lip 29, which when the parts are assembled is above an inwardly projecting lip 30 on one of the hinge lugs of the lever.

The advantages of my present invention lie in so shaping the parts that the bottom-operating lever will itself directly lift the locking block during at least a portion of its upward travel. This does away with the friction incident to lifting the lock by the knuckle-tail in opening, in which case rough surfaces might retard the opening movement. As the lock is now held entirely clear of even the raised portion of the knuckle tail until the knuckle has been entirely thrown open by the lever 17, the knuckle is permitted an easy rotation unhindered by any rubbing or frictional contact. At the same time the knuckle tail serves to hold up the lock in proper raised position when the operating lever is released, and until the knuckle is closed. This raised portion of the tail also serves to lift the lock off the lockset shelf when the knuckle is pulled open, at which time the frictional rubbing action is not material, as the knuckle is pulled open by the pulling apart of the cars. The abrupt cam surface of the lever 17 reduces friction between it and the operating lever, and gives a more efficient and easier action in knuckle-throwing.

I claim:—

1. A coupler having a knuckle, a vertically-movable locking device, a knuckle-throwing lever pivoted within the coupler and adapted to engage the locking device, an operating lever pivoted at the bottom of the coupler arranged to engage and actuate the knuckle-throwing lever, and a lug on said operating lever adapted to directly lift the lock during at least a portion of the movement of the operating lever.

2. A coupler having a knuckle, a vertically-movable locking block, a knuckle-throwing lever pivoted within the coupler and arranged to assist in actuating the locking block, and an operating lever pivoted at the bottom of the coupler, said lever having a part adapted to move the knuckle-throwing lever and a part adapted to directly lift the locking block for a portion of its upward movement.

3. A coupler having a knuckle, a verti-

cally-movable locking device, a knuckle-throwing lever pivoted within the coupler and arranged to engage the locking device, an operating lever pivoted at the bottom of the coupler adapted to engage and actuate 70 the knuckle-throwing lever, and a lug on said operating lever adapted to directly lift the locking device above the uppermost surface of the knuckle tail during knuckle throwing.

4. A coupler having a knuckle, a vertically-movable locking device, a lock-set lever pivoted within the coupler arranged to engage the locking device when said locking device is in lock-set position, and an operating lever pivoted at the bottom of the coupler having a part adapted to actuate the lock-set lever and a part adapted to directly lift the locking device into lock-set position.

5. A coupler having a knuckle, a vertically-movable locking device, a lever pivoted within the coupler adapted to throw the knuckle and also adapted to engage the locking device when said locking device is 90 in lock-set position, and an operating lever pivoted at the bottom of the coupler having a part adapted to actuate the first mentioned lever and a part adapted to directly lift the locking device.

6. A coupler having a swinging knuckle, a vertically-movable locking block, a knuckle throwing lever pivoted on a fixed pivot within the coupler, a side lug on said lever adapted to assist in lifting the locking block, 100 and a bottom operating element arranged to actuate directly the knuckle throwing lever and also to act directly upon the lock to lift it through a part of its movement.

7. In a coupler, a swinging knuckle, a vertically-movable locking block and a pair of co-acting levers arranged to successively engage the locking block, one lever being adapted to lift the locking block through one portion of its movement and the other 110 lever being adapted to lift it through another portion.

8. In a coupler, a swinging knuckle, a vertically-movable lock, and a pair of co-acting levers pivoted to swing in a vertical plane, 115 one of said levers being adapted to engage and lift the lock during one portion of its movement, and to engage and throw the knuckle during another portion of its movement, the other of said levers being adapted 120 to engage the first-named lever while said lever is lifting the lock, and to engage and lift said lock when the first-named lever is throwing the knuckle.

9. In a coupler, a swinging knuckle, a vertically-movable lock, a knuckle-throwing lever having a projection engaging one portion of the lock to act as a lock-to-the-lock, the said projection engaging another portion of the lock to hold it in lock-set position, a 130

raised portion on the knuckle-tail adapted to release the lock from lock-set position, and a bottom-operating lever arranged to directly engage and successively operate the 5 knuckle-thrower and the lock.

10. A coupler having a knuckle, a vertically movable locking block, a knuckle-throwing lever pivoted upon a fixed pivot within the coupler and adapted to co-act 10 with the locking block to prevent the locking block from creeping when the knuckle is in locked position, and a bottom-operating lever arranged to engage both the locking block and the knuckle-throwing lever thereby 15 releasing the lock and throwing the knuckle.

11. A coupler having a knuckle, a verti-

cally movable locking block, a knuckle throwing lever pivoted within the coupler and adapted to coact with the locking block 20 to hold the locking block in locked position when the knuckle is closed, and a lever pivoted at the bottom of the coupler having a part adapted to actuate the knuckle throwing lever and a part adapted to directly lift 25 the locking block through at least a part of its movement.

In testimony whereof, I have hereunto set my hand.

ARTHUR J. BAZELEY.
